UNITED STATES PATENT OFFICE.

ANKER PETERSEN, OF WINTHROP, MASSACHUSETTS.

TRAVERSE DRIVE FOR WINDING MACHINES.

Application filed September 8, 1923. Serial No. 661,713.

This invention pertains to machines for winding yarn or thread and relates more particularly to mechanism for actuating the traverse guide of such a machine, the 5 principal object of the invention being to provide a traverse guide mechanism of simple and durable character which will lay the yarn or thread with substantial uniformity from end to end of the building 10 yarn mass and wherein lost motion or back lash between the several parts is substantially eliminated.

A preferred embodiment of the invention together with certain modifications 15 thereof is illustrated by way of example in the accompanying drawings in which:—

Fig. 1 is a fragmentary front elevation of one end of a winding machine embodying the present invention;

20 Fig. 2 is a fragmentary end elevation from the right hand end of the device as viewed in Fig. 1;

Fig. 3 is a vertical section to larger scale on the line 3—3 of Fig. 2;

25 Fig. 4 is a fragmentary front elevation similar to Fig. 1 but showing a modification and

Fig. 5 is an end elevation of the parts shown in Fig. 4.

30 Referring to the drawings the numeral 1 indicates a portion of the frame of a winding machine of any desired type comprising a series of winding units of which the endmost is indicated at 2. The machine 35 is provided with a main shaft 3 which extends longitudinally of the frame and which is provided with a drum or series of pulleys 4 from which individual belts 5 extend to the several winding units for actuating 40 the latter. Each winding unit comprises a traversing yarn guide 6 mounted upon a reciprocating traverse bar 7 common to the several units and which may be supported and guided in any suitable manner.

45 A bracket 9 is secured to one end of the machine frame and this bracket is furnished with spaced bearings 10 and 11 for an oscillating shaft 12. The forward end of this shaft is provided with a cylindrical enlargement 13 preferably in the form of a spool secured to the shaft. An arm 15 extends 50 forwardly from the upper part of the bracket 9 and supports a stub shaft 16 upon which a guide drum 17 turns freely.

55 The traverse bar 7 projects beyond the end of the machine frame above the periph-

ery of the drum 17. Spaced brackets 18 and 19 respectively are secured to the end portion of the bar 7 and project horizontally in opposite directions from the bar. A 60 chain 20 has one of its ends secured to the bracket 18 and after passing over the peripheral surface of the drum 17 is wrapped about the spool 13 and its end is secured to the spool substantially at the point 21. A 65 second chain 23 has one of its ends secured to the bracket 19 and after passing about the opposite side of the drum 17 from the chain 20 has its end portion wrapped about the spool 13 and is secured to the latter 70 substantially at the point 24. The chains 20 and 23 are wrapped about the spool in opposite directions.

Below and substantially parallel to the shaft 16 a drive shaft 25 is mounted in 75 bearings 26 and 27 carried by the bracket 9. A worm wheel 28 is secured to the forward end of the drive shaft 25 and meshes with a drum 29 upon the end of the main shaft 3.

A countershaft 30 is arranged below and parallel to the shaft 25 and turns in bearings 31 and 32 carried by the bracket 9. The shafts 12, 25 and 30 all lie substantially in the same plane, the shafts 12 and 30 being disposed at diametrically opposite sides of the shaft 25.

A segmental driving gear 33 is secured to the drive shaft 25 and is arranged to mesh alternately with segmental gears 34 and 35 fixed respectively to the oscillating shaft 12 and to the countershaft 30. The shafts 12 and 30 project to the right beyond their bearings 11 and 32 and are furnished with large gears 36 and 37 which directly mesh with each other thus constraining the shafts 12 and 30 always to turn in opposite directions.

The hub of the gear 36 is provided with a crank pin 38 to which the upper end of a tension spring 39 is secured. This spring extends downwardly to a point below the shaft 30 and is secured to a fixed support 41.

In the modified arrangement illustrated in Figs. 4 and 5 the guide drum 17 illustrated in Figs. 1 and 2 is dispensed with and the oscillating shaft 12 drives a parallel shaft 41 by means of intermeshing gears 42 and 43. A wheel or disc 43 is secured to the shaft 41. This wheel or disc is provided with a peripheral groove which serves as a 105 guide for the outer end of a reciprocating

traverse bar 7^a. At opposite sides of the groove the wheel or disc is furnished with substantially cylindrical peripheral faces 43^b. A flexible connector 44, preferably consisting of a flat resilient strip of spring metal is secured at one end to a pin 45 projecting from the traverse bar 7^a. The flexible connector then passes about the wheel or disc 43^a engaging one of the peripheral surfaces 43^b at 46 and has its opposite end secured to the wheel or disc at the point 47. A second and similar flexible connector 48 is secured at one end to a pin 49 projecting from the opposite side of the bar from the pin 45 and this connector passes about the periphery of the wheel or disc 43^a engaging the other of the surfaces 43^b at 50 and has its opposite end secured to the wheel or disc at the point 51.

20 The mechanism described operates substantially as follows, the parts as shown in the several figures occupying the position which they assume when the yarn guide 6 is substantially at the middle of its stroke. 25 Main shaft 30 is constantly turning and by means of the worm 29 and wheel 28 constantly rotates the drive shaft 25 in a given direction, assumed to be that indicated by the arrow A in Fig. 3. As shown in the latter figure the segmental gear 34 carried by the oscillating shaft 12 is turning in a counterclockwise direction while the segmental gear 35 is out of mesh with the driving gear 33, but is constrained to move in a 35 clockwise direction by the action of the meshing gears 36 and 37.

The spring 39 is under tension and as the gears 33 and 34 continue their movement the crank pin 38 passes the center line of the 40 gears and immediately begins to react upon the shaft 12 and gear 36 tending to turn them in the same direction in which they are driven by the driving gear 33. This action gradually absorbs the back-lash between 45 the parts and when the endmost tooth T' of the driving gear has reached its lowermost position it immediately engages the first tooth T² of the gear 35, and motion is imparted to the gear 35 without hesitation 50 or lagging of the parts. The spring acts in the same manner when the driving gear 35 comes into engagement with the first tooth of the gear 34 so that the motion of the oscillating shaft 12 is smooth and certain. 55 The traverse bar 7 thus moves the yarn guide accurately so that the yarn is laid uniformly and smoothly upon the winding yarn mass without any tendency to pile up at the opposite ends of the latter as is usual 60 with traverse drive mechanism of ordinary character.

By employing the flexible but substantially non-extensible connections herein disclosed between the oscillating shaft and the 65 reciprocating traverse guide all lost motion

or back lash between these parts is also eliminated and the oscillatory movement of the shaft is transmitted without substantial change to the reciprocating bar.

In the device shown in Figs. 4 and 5 the 70 flexible resilient strips 44 and 48 take the place of the chains shown in Figs. 1 and 2 and transmit the motion from the oscillating shaft to the reciprocating bar in substantially the same manner. 75

The device thus provided is capable of application to existing winding machines without substantial change in their structure and while of simple character and comparatively cheap to construct provides for greater uniformity in laying the yarn upon the winding yarn mass than is usual in traverse drive mechanisms such as are commonly employed. 80

I claim:

1. In a winding machine having a reciprocating traverse bar provided with a thread guide, an oscillatory shaft, intermittent gears for driving the oscillatory shaft, a freely turning guide drum to which the bar is substantially tangent, a spool secured to the shaft, and a pair of chains engaging the spool, one end of each chain being secured to the bar and the other end portions of the respective chains being wrapped in opposite directions about the spool, the intermediate portions of the chains engaging opposite sides of the drum. 90

2. A traverse mechanism for winding machines having a reciprocating yarn guide and means for driving it comprising a gear constantly rotating in the same direction and a pair of segmental spur gears turning about axes parallel with the axis of the drive shaft, the axes of all of said gears lying in substantially the same plane, said segmental gears being arranged alternately to engage the driving gear, means for transmitting motion of one of said segmental gears to the other, means for transforming the intermittent rotary movement of the segmental gears into reciprocating motion, and means for transmitting such motion to the yarn guide. 100

3. A traverse mechanism having a reciprocating bar, an oscillating shaft, connections between the bar and shaft and means for oscillating the shaft comprising a rotating drive shaft, a segmental driving gear thereon, a segmental gear upon the oscillating shaft, a counter shaft, a segmental gear upon the latter, the segmental driving gear meshing alternately with the other segmental gears, and means connecting the segmental gear upon the counter shaft with the oscillating shaft. 115

4. Traverse mechanism having an oscillating shaft and means for oscillating the shaft comprising a rotating drive shaft, a segmental driving gear secured thereto, a gear 120

fixed to the oscillating shaft, a counter-shaft, a gear fixed to the latter, the segmental driving gear meshing alternately with said other gears, gears connecting the counter shaft and oscillating shaft arranged to compel said shafts to turn in opposite directions, and means reacting upon the oscillatory shaft tending to eliminate back-lash between the segmental driving gear and the gears 10 with which it alternately meshes.

5. Traverse mechanism having a reciprocating bar, an oscillating shaft, flexible connections between the shaft and bar for moving the latter, and means for oscillating the 15 shaft comprising a rotating drive shaft parallel to the oscillating shaft, a counter shaft parallel to the drive shaft and upon the diametrically opposite side thereof from the oscillating shaft, a segmental drive 20 gear on the driving shaft, gears secured to the oscillating shaft and counter shaft respectively, said gears meshing alternately with the segmental driving gear, constantly meshing gears mounted upon the oscillating 25 shaft and counter shaft respectively constraining said shafts to turn in opposite directions, and a spring reacting upon the oscillating shaft tending to eliminate back-lash between the intermittently engaging 30 gears.

6. Traverse mechanism comprising an oscillating shaft, a gear fast to the shaft, a gear intermittently meshing with the first named gear for turning the shaft in one

direction, means for turning the shaft in the opposite direction, a crank carried by the shaft, and a resilient device connected to the crank tending to take up back-lash between the gears as they approach operative engagement.

7. Traverse mechanism comprising an oscillating shaft, intermittently meshing gears for turning the shaft alternately in opposite directions, a crank carried by the shaft, and a spring secured at one end to the crank and at its other to a fixed support, the spring reacting through the shaft to take up back-lash between the gears as they approach operative engagement.

8. Traverse mechanism comprising an oscillating shaft, a rotating drive shaft parallel thereto, a counter shaft parallel to the drive shaft and diametrically opposite to the oscillating shaft, a segmental drive gear secured to the drive shaft, segmental gears alternately engageable with the drive gear secured respectively to the oscillating shaft and counter shaft, a gear secured to the counter shaft and directly meshing with a gear fixed to the oscillating shaft, a crank carried by the latter shaft, and a tension spring secured at one end to the crank and at its opposite end to a fixed support disposed substantially in the plane defined by the several shafts.

Signed by me at Boston, Massachusetts, this seventh day of September, 1923.

ANKER PETERSEN.
